REGULATOR MECHANISM FOR WINDOWS OF RAILWAY CARS AND THE LIKE

Filed March 23, 1935

UNITED STATES PATENT OFFICE

2,076,986

REGULATOR MECHANISM FOR WINDOWS OF
RAILWAY CARS AND THE LIKEBurton S. Floraday, Toledo, Ohio, assignor to
Dura Company, Toledo, Ohio, a corporation of
Ohio

Application March 23, 1935, Serial No. 12,592

4 Claims. (Cl. 268—126)

This invention relates to vehicles, but more particularly to windows and window frames for vehicles, such as railway cars and buses, and an object is to produce a new and improved window mounting for vehicles of this character by which the window can be conveniently raised and lowered by mechanism on which the window can be readily mounted, the window frame being removable to enable the window to be mounted or replaced without difficulty.

Another object is to produce a regulator mounting for windows of this character, which is readily accessible for repair or removing the window, and which affords maximum travel for the window within a minimum amount of space.

Other objects reside in the details of construction, arrangement and operation hereinafter described, and, for purposes of illustration, but not of limitation, embodiments of the invention are shown on the accompanying drawing, in which:

Figure 1 is a view in elevation of a portion of the inside of a vehicle body showing the window mounting and a portion of the upper panel broken away to show the regulator mechanism;

Figure 2 is an enlarged sectional elevation on the line 2—2 of Figure 1;

Figure 3 is an enlarged sectional elevation on the line 3—3 of Figure 1 showing the connection between one of the regulator arms and the window;

Figure 4 is an enlarged transverse sectional view on the line 4—4 of Figure 1 showing the mounting of the runways for the window;

Figure 5 is an enlarged vertical section on the line 5—5 of Figure 1 showing the sill structure; and

Figure 6 is an enlarged vertical sectional view of an alternate form of connection between the window and regulator.

The illustrated embodiment of the invention comprises a vehicle body 10 having a window opening 11 within which a window 12 is vertically movable. The sill for the window is in this instance made up of parts 13 and 13^a, which may be spot welded together at their centers and also spot welded, or otherwise suitably secured, to upright portions of the body. The end portions of the parts 13 and 13^a are shaped to provide a horizontal groove 14 in which is disposed a felt strip 15 against which the lower edge of the window 12 may seat when in lowered or closed position. As will hereinafter appear, the necessity for a well or sub-sill is obviated, the window 12 being raised with the upper portion

extending into a pocket or chamber above the window when moved to open position.

The vertical side edges of the window are guided in runways formed by a U-strip 16 covered by felt or fibrous material 17, the side edges of the window being bound by a channel strip 18. The runway 16 is suitably secured to a vertically disposed strip 19, which abuts against a U-shaped stamping 20, which is fixed at its rear end portion to a frame part 21. The oppositely disposed vertical edges of the frame parts 21 and 22 are turned inwardly and cover the rear portion of the runway 16. A substantially U-shaped strip 23 fits over the front end of the stamping 20 and has inturned end portions 24 which cover the front portion of the adjacent runways. It will be seen from an inspection of Figure 4 that the runway structures on opposite sides of the stamping 20 are the same, so that the adjacent window 12^a is similarly guided. Screws 25 hold the strip 23 in place so that by removing the screws and taking off the strip 23 the windows can be released from their runways.

Mounted on the upper longitudinal edge of the window 12 is a U-shaped rubber strip 26, which is clamped in place by a channel 27, to the rear surface of which is secured, as by spot welding, a plate 28, which projects upwardly beyond the channel 27. The upper portion of the plate 28 is provided with a substantially V-shaped depression 29 to receive similarly shaped portion 30 of a retainer 31, screws 32 connecting the retainer 31 to the plate 28. The front portion of the retainer 31 has a depending portion 32', which extends over the front portion of the channel 27. This portion of the retainer is secured to the channel 27 by screws 33, which extend through the depending portion 32', channel 27, and into a sleeve or holder member 34 disposed within the channel above the rubber strip 26.

Arranged above the window opening 11 is a regulator mechanism 35, which is a unitary structure having a mounting plate 36 secured by screws 37 and spacer sleeves 38 to a panel 39 forming part of the body. The panel 39 is secured to the body by screws 40 at the upper end thereof. The arrangement is such that by removing the screws 40 the panel 39 may be removed and with it the regulator mechanism.

The regulator mechanism 35 is of a well known type having a pair of arms 41 secured to gear segments 42 respectively, which mesh with each other so that the arms swing in opposite directions. One of the gears 42 meshes with a smaller gear 43, with which a larger gear 44 rotates. The gear 44

meshes with a pinion 45, with which is associated a well known clutch mechanism 46. Connected to rotate the pinion 45 is a handle 47 disposed on the outside of the panel 39. Counterbalancing 5 springs 48 are associated with each of the gear segments 42. Since the above described double arm regulator is well known in the art, detail description and explanation thereof is not considered necessary.

10 It will be seen that a stud 49 is disposed on the outer end of each of the arms 41, and, as shown in Figure 3, the stud is engageable in the channel or guideway formed by the retainer 41, a washer 50 pressed outwardly by coil spring 51 bearing 15 against the outer portion of the retainer to prevent rattles and cooperate with the flared outer end of the stud 49 to hold it in the desired position. It will be apparent that by turning the handle 47 in one direction or the other the studs 20 49 travel in opposite directions in the slotted panel 31 and operate to raise or lower the window.

When it is desired to remove the window the screws 32 and 33 are removed to disconnect the retainer 31 from the channel 27, thereupon by 25 turning the handle 47 the retainer may be moved away from the window to leave the upper edge thereof free therefrom. Thereafter, by removing the strips 23, it will be apparent that the window 30 can be readily replaced.

35 In the form shown in Figure 6, the parts are similar to the structure shown in Figure 3 except the strip 28^a is secured as by spot welding to the retainer 31^a, thereby dispensing with the screws 32. The bolt 33^a projects entirely through the channel 27^a as well as the strip 28^a, and a part 51 fixed to the rear side of the strip 28^a and screw threaded to receive the bolt 33^a. It will thus be seen that a series of bolts 33^a may be removed, 40 after which the retainer 31^a can be separated from the channel 27^a, and thereby separate the regulator mechanism from the window.

45 It is to be understood that numerous changes in details of construction, arrangement and operation may be effected without departing from the spirit of the invention, especially as defined in the appended claims.

What I claim as new and desire to secure by Letters Patent is:

50 1. In a device of the class described, a unitary regulator assembly having a swinging arm, a retainer having an elongate guide to receive an end portion of said arm, a channel member secured to an edge portion of the window, a portion of said 55 retainer overlapping said channel member, a holding member carried by said channel member, detachable fastening devices extending through

said overlapping portions engaging said holding means which secure the parts together, a strip secured to said channel member and overlapping said retainer member, and detachable means securing said strip and retainer member together. 5

2. In a device of the class described, a unitary regulator assembly having a swinging arm, a retainer having an elongate guide to receive an end portion of said arm, a channel member secured to an edge portion of the window, a portion of said retainer overlapping said channel member, a holding member carried by said channel member, detachable fastening devices extending through 10 said overlapping portions engaging said holding means which secure the parts together, a strip fixed to said retainer member and overlapping said channel member, and a detachable securing device extending through the overlapping portion of said retainer member through said channel member and holding means and the overlapping portion of said strip, thereby detachably to secure 15 said parts together. 20

3. In a device of the class described, a regulator assembly having a swinging arm provided with a stud on the free end thereof, a retainer member having a guide to receive said stud of substantially U-shape in cross-section, a channel member adapted to be secured to an edge portion 25 of a window, the vertically disposed sides of said retainer and channel being approximately flush with each other so that said arm is disposed in a plane close to said channel member overlapping side portions on said members, and detachable fasteners engaging said overlapping portions 30 for connecting said retainer and channel members. 35

4. In a device of the class described, a regulator assembly having a swinging arm provided with a stud on the free end thereof, a retainer member having a guide to receive said stud of substantially U-shape in cross-section, a channel member adapted to be secured to an edge portion of a window, the vertically disposed sides of said retainer and channel being approximately flush 40 with each other so that said arm is disposed in a plane close to said channel member, a flange on 45 said retainer overlapping said channel member on one side, means on one of said channel and retainer members and engaging the other of said members on the opposite side for cooperating in holding the parts in position, and detachable fasteners passing through said flange and engaging 50 said channel member. 55
